UNITED STATES PATENT OFFICE.

HORACE BARTLETT WYMAN, OF MINNEAPOLIS, MINNESOTA.

CARBURETER.

1,133,904.

Specification of Letters Patent. Patented Mar. 30, 1915.

Application filed April 4, 1914. Serial No. 829,514.

To all whom it may concern.

Be it known that I, HORACE B. WYMAN, a citizen of the United States, residing at Minneapolis, in the county of Hennepin and 5 State of Minnesota, have invented certain new and useful Improvements in Carbureters, of which the following is a specification.

My invention relates to improvements in 10 carbureters, for use in connection with internal combustion engines, and has particular reference to a carbureter designed to maintain constant the relative volumes of air and gasoline or the like, independently 15 of the change of the load upon the engine.

An important object of the invention is 20 to provide a carbureter of the above mentioned character, which is of simple construction, inexpensive to manufacture, and is automatic in operation.

A further object of the invention is to provide means for maintaining the relative volumes of air and gasoline or the like constant, such means discharging the air 25 and gasoline or the like into proximity to each other so that they will become thoroughly mixed.

A further object of the invention is to provide a carbureter of the above mentioned 30 character designed to maintain constant the relative volumes of air and gasoline or the like, and having adjustable means to permanently vary the relative volumes of air and gasoline or the like.

35 Other objects and advantages of the invention will be apparent during the course of the following description.

In the accompanying drawings forming a 40 part of this specification and in which like numerals are employed to designate like parts throughout the same, Figure 1 is a side elevation of a carbureter embodying my invention. Fig. 2 is a central longitudinal sectional view through the same, Fig. 3 is 45 a horizontal sectional view taken on line 3—3 of Fig. 2, Fig. 4 is a similar view taken on line 4—4 of Fig. 2, and, Fig. 5 is an enlarged detail section through the gas outlet valve structure.

50 In the drawings, wherein for the purpose of illustration is shown a preferred embodiment of my invention, the numeral 10 designates a main carbureting shell or chamber of the carbureter, which is preferably vertically arranged and provided upon one side 55 thereof and near its upper end with an out-

let passage or port 11, to be connected with the cylinder or cylinders of an internal combustion engine, whereby the carbureted air is sucked from the shell 10, during the 60 operation of the engine, as is customary.

Mounted within the port or passage 11 is a valve 12, preferably of the butterfly type, the same being rigidly mounted upon a rock-shaft 13, journaled through the wall 65 of the port or passage 11 and extending outwardly beyond the same.

Secured to the outer end of the rock-shaft 13, exteriorly of the shell 10, is a crank 14, adapted to be moved by any suitable means. 70

Arranged below the lower open end of the shell or chamber 10 is a tubular portion or sleeve 15, secured thereto, as shown at 16, such union being air-tight, as is obvious. As more clearly shown in Figs. 2 and 4, 75 the tubular portion 15 is provided with a diametrically arranged web or member 17, preferably cast integral therewith, a portion 18 of the same being tubular and extending outwardly beyond the tubular portion 15, as shown at 19, for connection with a fuel supply pipe, containing gasoline, kerosene oil, or the like. The supply tube 18, at its inner end, is in free communication with a vertical fuel discharge tube or 80 element 20, arranged within the shell 10 and tubular portion 15, preferably in spaced concentric relation thereto. The amount of the fuel, such as gasoline or kerosene oil, passing through the discharge tube 20, may 85 be permanently regulated by means of an adjusting valve 21, the pointed end of which is adapted to engage and disengage the lower end of the fuel discharge tube 20, as shown.

As more clearly shown in Fig. 5, the fuel 90 discharge tube 20 is provided at its upper end with an enlarged counter-bore 22, which is frusto conical in vertical cross-section and increases in diameter upwardly. At its extreme upper end, the fuel discharge tube 100 20 is beveled, as shown at 23, forming a seat for a vertically movable valve 24, carried by or formed upon a stem or rod 25. Depending from the valve seat 24 is a circumferentially reduced shank 26, preferably 105 cylindrical, and adapted to extend to the lower end or bottom of the counterbore 22, when the valve 24 is closed or seated, as is obvious from Fig. 5.

The stem 25 has its upper end mounted to 110 reciprocate through an opening 27, and is provided with an upstanding extension 28,

extending through a tubular housing 29. Surrounding the extension 28 and engaging the upper end of the stem 25 is a compressible coil spring 30, the upper end of which is 5 arranged within and engages an adjusting cap 31, having screw-threaded engagement with the tubular housing 29, as shown. The function of the spring 30 is to urge the valve 24 toward its seat, the tension of the spring 10 being adjusted by manipulation of the cap 31. The stem 25 is provided with a screw-threaded portion 32, engaged by an internally screw-threaded sleeve 33, having pivotal connection with a link 34, the upper end 15 of which is pivotally connected with a vertically swinging lever 35, pivotally supported between its ends, as shown at 36. The upper end of the lever 35 is connected with a link 37, pivotally connected with a suction 20 actuated plunger 38, mounted to reciprocate within an outwardly extending cylinder 39, formed upon the shell 10, as shown. The upper end of the cylinder 39 is preferably closed by an apertured cap 40, as shown. It 25 is thus that upon the increase of suction or vacuum within the shell 10, the plunger 38 will be drawn inwardly, lever 35 swung in one direction to raise the lower end thereof, whereby stem 25 will be elevated and valve 30 24 moved away from its seat, in opposition to the spring 30. Having screw-threaded engagement with the lower screw-threaded portion 32 is a control tube 41, extending downwardly beyond the shank 26 for a substantial distance and receiving the fuel discharge tube 20, as shown. Adjacent the shank 26 the control tube 41 is provided with apertures 42, adapted to be moved above the upper end of the discharge tube 40 20, upon the upward movement of the stem 25. The size and number of these apertures 42 are proportioned to maintain constant the relative volume of gasoline and air, the means for controlling the supply of air being arranged outwardly of and adjacent 45 these apertures.

The means for controlling the passage of the air into the shell or chamber 10, such air passing inwardly through the lower end of 50 the tubular portion 15, through passages 43, (see Fig. 4), comprises a plurality of vertically swinging valve-plates or elements 44, which are substantially triangular, normally inclined, and decrease in width upwardly. At their lower or outer ends the valve-plates 44 are hinged to the tubular portion 15, as shown at 45 and the same are provided at their upper or inner ends with curved recesses 46, forming a cylindrical opening to receive the control tube 41. This opening, when the valve-plates 44 are closed, is slightly larger in diameter than the tube 41, providing a contracted permanent passage for the air. Depending from the valve- 55 plates 44 are cranks 47, rigidly connected

therewith, with which are pivoted links 48, pivotally connected with the vertically movable tube 41, as shown. It is thus seen that as the stem 25 is elevated, as above stated, the valve-plates 44 are swung upwardly toward the open position. 70

I provide electrical means to heat the liquid fuel before the same is discharged from the tube 20, comprising a heating coil 49, surrounding the lower portion of the tube 20, as shown in Fig. 2. A heating coil 50 is also arranged within the lower end of the tubular portion 15, for the purpose of heating the air passing therein. The heating coils 49 and 50 are preferably connected in series by a wire 51, the coil 49 being connected with one pole of a source of current (not shown) by a wire 52 while the heating coil 50 is connected with the opposite pole of the source of current by a wire 53. 80

The operation of the carburetor is as follows:—The valve 12 is partially or completely opened, and the engine started. The operation of the engine creates a suction within the shell 10, whereby upon the increase of this suction or vacuum, due to the increase of the load upon the engine or the like, the plunger 38 will be moved inwardly, whereby the stem 25 will be elevated. This movement of the stem 25 moves the valve 24 farther away from its seat and also elevates the control tube 41 whereby an increased number of the openings 42 are arranged above the upper end of the discharge tube 20. An increased amount of liquid fuel is accordingly supplied through the apertures 42 into the shell 10. A proportional increase in the supply of air is also obtained, as upon the upward movement of the tube 41 the valve-plates 44 are swung upwardly, increasing the size of the air opening at 46. Particular attention is called to the fact that by using the valve-plates 44 arranged in the annular row around the control tube 41, such valve-plates being also inclined, the air is deflected inwardly and upwardly, and made to travel in proximity to the exterior of the apertures 42, to become intimately mixed with the liquid fuel. 105

It is to be understood that the form of my invention herewith shown and described is to be taken as a preferred example of the same, and that various changes in the shape, size and arrangement of parts may be resorted to without departing from the spirit of the invention or the scope of the subjoined claims. 110

Having described my invention, I claim:—

1. In a carburetor of the character described, a carbureting shell, a liquid fuel supply tube extending axially within the carbureting shell, a plurality of vertically swinging valve plates arranged within the carbureting shell and surrounding the liquid fuel supply tube to control the passage of 125

- air through the carbureting shell in proximity to the supply tube, a perforated tube slidably mounted upon the supply tube to move longitudinally thereof and extending 5 upwardly beyond the outlet end of the supply tube, connecting means between the valve plates and the perforated tube whereby upon the upward swinging movement of the valve plates the perforated tube is simultaneously moved upwardly, a valve connected with and extending into the upper end of the perforated tube to engage and disengage the upper end of the supply tube, and suction operated means connected with 10 the valve to automatically move the same.
2. In a carbureter of the character described, a carbureting shell, a liquid fuel supply tube extending axially within the carbureting shell, a plurality of vertically 15 swinging valve plates arranged within the carbureting shell and surrounding the supply tube to control the passage of air through the carbureting shell in proximity to the supply tube, a perforated tube slidably 20 mounted upon the supply tube to move longitudinally thereof and extending upwardly beyond the outlet end of the supply tube, cranks connected with and depending from the valve plates, links arranged below the 25 valve plates and connecting the cranks and the perforated tube, a valve connected with the perforated tube and extending therein for a substantial distance to engage and disengage the upper end of the supply tube, a 30 suction operated device, and connecting means between the suction operated device and the valve.
3. A carbureter of the character described, a carbureting shell, a liquid fuel supply tube 35 extending axially within the carbureting shell, a plurality of vertically swinging valve plates arranged within the carbureting shell and surrounding the liquid fuel supply tube to control the passage of air through the carbureting shell in proximity to the supply tube, a perforated tube slidably mounted 40 upon the supply tube to move longitudinally thereof and extending upwardly beyond the 45
- upper outlet end of the supply tube with its upper end internally screw-threaded, operative connecting means between the valve plates and the perforated tube, a valve having its lower end screw-threaded to engage within the upper screw-threaded end of the perforated tube to engage and disengage the 50 outlet end of the supply tube, a spring to oppose the upward movement of the valve, a pressure operated device arranged within the shell above the valve plates, a pivoted lever, means connecting the pivoted lever with the 55 pressure operated device, and means connecting the pivoted lever with the valve.
4. In a carbureter of the character described, a carbureting shell, a liquid fuel supply tube extending into the same, a valve 60 movable toward and away from the outlet end of the liquid fuel tube, a perforated control tube connected with the said valve for movement therewith and receiving the liquid fuel supply tube therein, and a valve 65 arranged within the carbureting shell and formed of a plurality of swinging valve plates connected with the said valve to be moved upon the movement thereof and means to move the said valve.
5. In a carbureter of the character described, a carbureting shell, a liquid fuel supply tube extending into the same, a valve 70 movable toward and away from the outlet end of the tube, a perforated control tube connected with the valve to move therewith and receiving the tube therein, a plurality of vertically swinging valve-plates arranged 75 within the mixing shell and surrounding the perforated control tube, operative connecting means between the valve-plates and the control tube, and suction operated means connected with the liquid fuel supply valve to move the same.
